UNITED STATES PATENT OFFICE.

FRIEDRICK RENZ, OF PROVIDENCE, RHODE ISLAND, ASSIGNOR TO SPEIDEL CHAIN CO., A FIRM COMPOSED OF FREDERIC SPEIDEL AND EUGEN SPEIDEL, OF PFORZHEIM, GERMANY, DOING BUSINESS IN PROVIDENCE, RHODE ISLAND.

CHAIN.

Application filed July 2, 1928. Serial No. 289,858.

This invention relates to a chain for use as a bracelet for wrist watches or the like; and has for its object to provide a thin flexible band which when worn on the wrist 5 for attaching a watch thereto will not interfere with the use of the wrist for writing or otherwise inconvenience the wearer of the same.

A further object of the invention is to 10 provide a construction which will withstand longitudinal strains without separation and which presents an attractive appearance when worn.

This invention further consists in the 15 connecting together of a sheet metal body link by a frame link with portions of the body link folded to substantially completely house and hide the connecting links from view.

20 With these and other objects in view, the invention consists of certain novel features of construction, as will be more fully described, and particularly pointed out in the appended claims.

25 In the accompanying drawings:

Fig. 1 is a top plan view on an enlarged scale of the chain formed in accordance with this invention.

Fig. 2 is a view looking at the under side 30 thereof with some of the links partially in section to better show the construction thereof.

Fig. 3 is a perspective view of the frame link.

35 Fig. 4 is a perspective view of the cut out blank of the body link before being bent into shape.

Fig. 5 is a perspective view of the body 40 link with the wing portions thereof bent into position to receive the frame links.

Fig. 6 is a perspective view showing two of the frame links as connected by a body link in the position illustrated in Fig. 5.

Fig. 7 is a perspective view showing the 45 wings folded into the position which they assume in the finished construction.

Fig. 8 is a perspective view showing the 50 edge extensions as also bent into position which they assume in the finished construction.

Fig. 9 is a section showing the wings as bent into final position with the edge extensions as partially bent toward final position.

Fig. 10 is a section similar to Fig. 9 with

the edge extensions bent into final position 55 as illustrated in Fig. 8.

Fig. 11 is a section on line 11—11 of Fig. 8.

Fig. 12 is a top plan view of a modified construction showing the edge extensions as terminating at the edge of the frame links. 60

It is found desirable in chain structures of the type to be worn as a band or strap, to secure a watch on the wrist, of advantage to provide a construction of a minimum thickness to avoid obstruction of the use of 65 the wrist for writing purposes and the like and to give a neat appearance when worn; and in order to accomplish this result I have connected together frame links by sheet metal body links such that the thickness of 70 the combined construction is substantially twice the thickness of the body link plus the thickness of the frame link and in so doing I have provided an extremely strong and durable construction which will withstand 75 the longitudinal strain to which it is subjected without the separating of any of the parts; and the following is a detailed description of the present embodiment of this invention illustrating the preferred means 80 by which these advantageous results may be accomplished:

With reference to the drawings, 15 designates the frame link which is generally rectangular in shape and provided with a rectangularly shaped opening 16 leaving bars 17 and 18 about which wing portions 19 extending from the body portion 20 of a sheet metal connecting link are folded. The edges 21 and 22 of the wings abut to form 85 a portion of the back wall of the body link and extending portions 23 of the same width as the body 20 are formed on the edges thereof to cover the top surface of the frame 90 links and are folded about the edges of the frame links, as illustrated at 24, see Fig. 8, with their extremities 25 abutting the edge portions 26 and 27 of the wings to complete 95 the back wall of the body link and house a portion of each of the connected frame links 100 therein.

Each of the parts of this bracelet is of thin sheet stock and the thickness of the chain as a whole is substantially the combined thickness of twice that of the sheet stock of the body link plus that of the frame link. 105

In some cases the top of the body link is

extended as at 28, see Fig. 12, a distance to cover the upper part of the frame link without being bent around the edge thereof to partially hide the frame link and improve 5 the appearance of the chain.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

- 15 1. A bracelet chain comprising a series of generally rectangularly-shaped frame links, a sheet metal link having a body with oppositely extending wings, each positioned thru a frame link in contact with the body and folded together with their ends abutting and edge extensions on said body of a width substantially that of the body folded about the edges of adjacent frame links and abutting the edges of said folded in wings to 20 25 form complete top and bottom walls, whereby the frame links are hidden from view from either the top or bottom of the chain.
2. A bracelet chain comprising a series of generally rectangular frame links, each with a generally rectangular opening there-through, sheet metal links each having a body of a length substantially the length of said opening with wings substantially the length of said openings extending there-through and folded together with their ends abutting, and edge extensions on said body of a width substantially the width of the body folded to provide top, edge and bottom 30 35 40 portions and abutting the edges of the wings and covering the edge portions of the frame links.

3. A bracelet chain comprising a series of

sheet stock frame links, sheet stock links connecting the same, each connecting link having a body portion against which the portions of adjacent frame links contact, wing portions folded about said frame links and substantially in contact with the opposite sides thereof, and edge portions extending from said body over the edge portions of said frame links to partially hide the same, whereby an extremely thin construction is provided. 45 50

4. A bracelet chain comprising a series of sheet stock frame links, sheet stock links connecting the same, each connecting link having a body portion against which the portions of adjacent frame links contact, wing portions folded about said frame links and substantially in contact with the opposite 55 60 sides thereof and edge portions folded about the edges of adjacent links and meeting the edges of said wing portions, whereby an extremely thin construction is provided.

5. A bracelet chain comprising a series of body links, each formed of a sheet stock base with wings folded into abutting relation at the bottom thereof and edge extensions to abut the bottom edges of the wings, and connecting links embracing said wings of 65 70 adjacent body links and confined between said base, said wings, and said extensions.

6. A bracelet chain comprising a series of body links, each formed of a sheet stock base with wings folded into abutting relation at 75 the bottom thereof and edge extensions folded to abut the bottom edges of the wings, and connecting links embracing said wings of adjacent body links and confined between said base, said wings, and said extensions, 80 and substantially covered thereby.

In testimony whereof I affix my signature.

FRIEDRICK RENZ.
